UNITED STATES PATENT OFFICE.

PIERPONT E. DUTCHER, OF UPPER MONTCLAIR, NEW JERSEY.

DIGGING AND LOADING MACHINE.

Application filed October 6, 1922. Serial No. 592,819.

To all whom it may concern:

Be it known that I, PIERPONT E. DUTCHER, a citizen of the United States, and resident of Upper Montclair, in the county of Essex and State of New Jersey, have invented a new and useful Improvement in Digging and Loading Machines, of which the following is a specification.

This invention relates to a digging and loading machine, and has for an object to provide such an apparatus which embodies a pair of elongated arms that are provided with digging mechanism and are adapted to be advanced into the material in V formation.

Another object consists in providing the digging arms with chains which carry the digging elements and are actuated in an elongated endless path.

20 Another object consists in providing means for adjusting the angularity of the digging arms with respect to each other.

Another object consists in arranging the transverse axis of the digging arms at an angle to the horizontal so that their advancing edges are immediately adjacent the surface of the street or other surface upon which the material is lying.

Another object consists in arranging the 30 digging arms so that the material which has been dug is, at the point of discharge, fed upwardly at an angle by the digging elements themselves.

Another object consists in providing an 35 improved form of digging elements which includes means for cutting, sawlike, underneath the material to be carried away, as well as means for digging into and moving the material.

40 Another object consists in providing the chains which carry the digging elements with means for supporting and guiding them in a true course both vertically and horizontally.

45 Another object consists in providing means for withdrawing the digging elements within the path of travel of their carrying chains in order to scrape the material from said elements, together with means for scraping the adhering material off the chains, so that the entire load carried by the elements may be fed to the loading mechanism.

50 Another object consists in providing an arrangement whereby means, separate from the machine proper, may be used for pro-

pelling it, steering it and driving the mechanism, said arrangement being such that the mechanism may be continuously actuated no matter what the relative position of the 60 propelling means and the machine.

Another object consists in providing for adjustability of the several parts in order to enhance its operative features of value.

Another object consists in providing cer- 65 tain improvements in the form, construction and arrangement of the several parts whereby the above named and other objects may be effectively attained.

A practical embodiment of the invention 70 is represented in the accompanying drawings in which—

Fig. 1 represents a side elevation of the machine and part of the truck for propelling it.

75

Fig. 2 represents a plan view thereof.

Fig. 3 represents a rear view thereof, parts being removed.

Fig. 4 represents a front view thereof.

Fig. 5 represents a vertical central section 80 therethrough.

Fig. 6 represents a detail plan view, partly in section, showing part of the framing and drive mechanism.

Fig. 7 represents an enlarged detail plan 85 view, partly in section, of one of the digging arms.

Fig. 8 represents a section taken in the plane of the line VIII—VIII of Fig. 7, looking in the direction of the arrows.

90

Fig. 9 represents, on the same scale, a side elevation, partly broken away, of the digging arm shown in Fig. 7.

Fig. 10 represents, on the same scale, a top plan view of one of the digging arms 95 and connected parts.

Fig. 11 represents, on the same scale, a transverse section taken in the plane of the line XI—XI of Fig. 10 looking in the direction of the arrows.

100

Fig. 12 represents an enlarged detail plan view, partly in section, of the feed board upon which the material is deposited by the digging arms.

Fig. 13 represents, in the same scale, a 105 detail side view, partly in section, of the same.

The machine has a supporting frame (Fig. 6) which consists of longitudinal members 1, 2 that are composed of suitable 110 material, such as wood or metal, and arranged in V formation. At the apex, these

members are firmly secured together by cross plates 3, 4 and, intermediate their ends, by cross bars 5, 6. In the separated ends of the members 1, 2, there is mounted at 7, 8 a dead axle 9 which has wheels 10, 11 on its protruding ends. These wheels serve for the support and movement of the machine as a whole.

The body framing of the machine (Figs. 1 and 2) includes two main side members 12, 13 which may conveniently be composed of timber; and two independent side members 14, 15. The members 12, 13 are spaced from the members 14, 15 both in a vertical and horizontal direction. The independent members 14, 15 are secured to each other by cross bars 16, 17, 18, 19, 20, 21, and bars 17 and 21 are extended so as to connect members 12 and 13 with members 14 and 15. The cross bar 21 is a stout one and is calculated to rest upon the axle 9 with the members 12, 13 lying above the said axle and the members 14, 15 lying therebelow. As a result of this arrangement, the framing just described has, in effect, a bifurcated end which is supported upon the axle 9 with the framing projecting rearwardly and upwardly in an angular direction.

The framing also includes a pair of top members 22, 23 which are supported from the members 12 and 13 by uprights 24, 24, 25, 25, 26, 26, 27, 27. The forward ends of the top members 22, 23 are connected by a cross piece 28, while diagonal braces 29, 29, 30, 30 and a cross brace 31 serve rigidly to hold the parts.

A pair of arms 32, 32 (Figs. 1 and 5) are bolted to the uprights 27, 27 and project forwardly. Another pair of arms 33, 33 are also secured to the uprights 27, 27 and project forwardly therefrom below the arms 32, 32. The free ends of the arms 32, 32 are bored to form bearings for pivot pins 34, 34 which constitute supports and pivots for the upper connection of the digging arms.

The two digging arms are identical so that only one will be described in detail, reference being had to Figs. 7 to 11. The arm includes an open frame-work which may be composed of wood or other suitable material and consists of top members 35, 36, 37, 38 and bottom members 39, 40, which top and bottom members are secured to each other by vertical bars 41, 42, 43, 44. A plate 45 is secured to the bottom members 39, 40 and projects forwardly, its free end being provided with a bearing 46 that receives the end of a shaft 47, the upper end of which is fitted in a bearing 48 that is secured to the top members 36, 37. Another shaft 49 has its upper end journaled in a bearing 50 that is secured to the top members 36, 37 and its lower end journaled in another bearing 51 that is attached to the

inner ends of the members 39, 40. The bearing 51 has a projection 51° that is rotatably mounted in the arm 33, as clearly shown in Fig. 11. The bearing 50 has offset lugs 52 that are bored to receive the pivot pin 34. As already indicated, it is the inter-engagement of this pin and arm 32, together with the inter-engagement of projection 51° on bearing 51 and arm 33, that constitutes the connection between the digging arm and the machine as a whole, while also providing a pivot upon which the digging arm may be adjusted, when desired, in the use of the machine. As a result of forming the upper bearing for the pin 34 in the lugs 52 which are offset from the bearing 50, the said pin has its axis at an angle to the axis of the shaft 49 and, as the pin 34 and the part 51° of bearing 51 which enters arm 33, are in vertical alignment, the shaft 49 is at an angle to the vertical so as to hold the digging arm as a whole tilted with its transverse axis at an angle to the horizontal and its longitudinal axis substantially horizontal, as clearly shown in the drawings, the tilting of the arm being so arranged as to bring its inner or forward edge closer to the ground or surface upon which the material is resting, than is the remainder of the arm. This enables the advancing edge of the cutting elements to dig into or cut under the material in an advantageous manner and also clears the way, during the advancing movement of the arm, for other parts of the arm which project from its bottom, such, for instance, as the mountings or bearings for the shafts 47 and 49.

Pairs of sprockets 53 and 54 are fixed on the shafts 47 and 49 respectively between the upper and lower surfaces of the digging arm, and are surrounded by a sprocket chain 55 which carries the digging elements proper, and is covered with plates 55° (Figs. 8 and 11) except where the elements project therethrough. Each element consists of two angular arms 56 which swing on a pintle 57 of the sprocket chain and have a broad concave face blade 58 adapted to dig into and carry along the material. The curve of each blade 58 corresponds to an arc having as its center a pintle 57 so that, as the blade is swung inwardly (in a manner to be hereinafter described) its surface will be scraped free of the material by reason of the sliding contact with the adjacent plate 55° on sprocket chain 55. Each digging element also includes a knife 59 which is secured to the chain immediately below the lower edge of the concave face 58. The knife 59 is sharp and pointed, as clearly shown in Fig. 7, and is admirably designed to cut into and under the material which lies close to the surface such, for instance, as a layer of ice formed on a street surface.

The knives 59 are fixed in position on the sprocket chain 55 so as to always protrude from the outside of the digging arm as a whole and to operate somewhat after the 5 manner of a saw cut owing to the intervening spaces between the knives. The digging blades 58 are adapted to be projected and retracted from the outer surface of the chain 55 as the operation of the device may 10 require. To this end, I provide a pair of cams 60 which are carried by the vertical bars 41, 42, 43, 44, and are tapered on their rear sides from their free ends inwardly so as to be wider adjacent the advancing end of the 15 digging arm and narrower near the point where the digging arm is attached to the machine as a whole. In addition to the cams 60, I mount a box cam 61 on the shaft 49, which box cam cooperates with the cams 20 60 in actuating the digging elements 56. Each of the said elements 56 is provided with a pair of rollers 62 which engage the periphery of the cams 60 and travel in the groove formed in the box cam 61. As a result 25 of this arrangement, it will be seen that the cams 60 prevent the digging elements 56 from swinging inwardly about their pivots 57 more than a predetermined distance, while the box cam 61 serves positively 30 to draw the said elements inwardly with respect to the outer surface of the chain 55. The arrangement of this cam is such that, as clearly shown in Fig. 7, the elements 56 are projected to the utmost at the time 35 they pass around the forward end of the arm so that they may dig as deeply as possible into the material. The digging elements are then maintained in extended position as they move inwardly toward the loading 40 mechanism (to be hereinafter described) but, after the material carried by the said elements is in position to be deposited upon the loading mechanism, the box cam 61 comes into action and withdraws the elements 45 until they are entirely housed within the chain 55. This condition exists just as or before each element passes the loading mechanism. As already indicated, this inward swinging movement of the digging 50 elements takes place with their curved faces in sliding contact with plates 55* on the chain 55, thereby positively removing the material from the digging elements. Furthermore, this housing of the digging 55 elements within the surface of the chain permits the latter to be acted upon by a scraper (to be hereinafter described) which constitutes part of the loading mechanism, in such manner as to insure the removal of all 60 the material from the chain. Subsequently, the cams 60 gradually move the digging elements outwardly until they reach their fully extended position just before arriving at the outer or digging end of the advancing 65 arm.

The point at which the digging elements should be withdrawn by the cam 61 will vary slightly according to the angular adjustment of the digging arm about the pivot 34, since the said angular adjustment will 70 slightly vary the relationship of the digging elements to the loading mechanism. In order to accomplish this result, I mount the box cam 61 so that it can be rotatably adjusted about the shaft 49, and provide a 75 latch 63 which is secured to the cam 60 at 64, and has a finger fitted to enter any one of a series of recesses 65 formed in the cam 61. By this mechanism, the said cam may be locked in the desired adjustment about 80 the shaft 49 and hence come into operation at different stages in the travel of the digging elements 56. It is not necessary thus to withdraw the cutting knives 59, since 85 they are located near the bottom of the digging arm, and are very thin so as to pass under adjacent parts of the loading mechanism.

In order to prevent the sprocket chain 55 from sagging, I provide it with a series of 90 rollers 66 which travel upon tracks 67 secured to beams 68 that are fastened to the top members 35 and 38. Another series of rollers 69 are mounted at the tops of the chain pintles 57 so as to travel within and 95 adjacent to a peripheral flange 70 that is secured to the top members 35, 36, 37, 38 and surrounds the digging arm as a whole. Thus, these rollers 69, in cooperation with the flange 70, prevent the chain from moving 100 outwardly at any point a sufficient distance to move one or more of the rollers 66 off the track 67 and thereby permit the chain to sag at that point.

Means is provided for driving the shaft 105 49 of each digging arm (Figs. 2, 5 and 6), which means includes a pair of bevel gears 71, 72 fixed to the shafts 49 and meshing with bevel pinions 73 that are carried on the ends of shafts 74. The shafts 74 are suitably 110 provided with universal joints 75 and slip joints 76, and the rear portions of said shafts are mounted in bearings 77, 77, 78, 78, and 79, 79 which are fastened to the uprights 25, 25, 26, 26 and plates 80, 80 which latter are 115 carried by the members 12, 13. Each of the shafts 74 has a sprocket 81 secured thereto while sprocket chains 82 run from said sprockets to other sprockets 83 fixed on the main shaft 84 which is journaled in bearings 120 85, 86, 87, 88 that are mounted on the cross bars 5 and 6 and the plates 3 and 4 respectively. The rear end of the main shaft 84 has a universal connection 89 with a short shaft 90 that is mounted in bearings 91 supported on a tongue 92 which is carried by a truck 93 or similar means for propelling, steering and imparting power to the machine. A sprocket 94 is fixed on the shaft 90 and connected by a chain 95 with another 125 130

sprocket 96 that is driven by the engine of the truck 93. A manually operable clutch 97 serves to engage and disengage the shaft 84 with and from the source of power in the truck 93. When the clutch 97 is engaged, it will be clear that the shafts 49 of the digging arms are driven through the chain of the mechanism just described and that they, in turn, drive the chains 55 which carry the digging elements 56 and 59. By inverting the bevel gear 72 (Fig. 2), the chain of its digging arm is driven in an opposite direction from the chain of the other digging arm so that the digging elements will travel in an inward or rearward direction along the inner sides of both digging arms. As previously indicated, the digging arms are mounted in a tilted or angular position and are adapted to be swung around their pivots 34 for suitable adjustment. This swinging movement of the digging arms will slightly change the position of the bevel gears 72 mounted on the shafts 49, and it is therefore desirable, if not necessary, to allow for compensating bodily movement of the bevel pinions 73 in order to maintain proper meshing of these sets of gears. This movement of the pinions 73 is accomplished by mounting the ends of the shafts 74 to which they are secured, in floating brackets 98 which have bifurcations 99 embracing the shafts 49 while their rear ends have a universal pin and slot connection with the uprights 27, as clearly shown in Figs. 1 and 5. This pin and slot connection is accomplished by forming a horizontal slot 100 in the tail of each bracket 98 and a vertical slot 101 in each upright 27. Double headed pins 102 pass through both these slots so as to hold the parts in loose connection.

The loading mechanism may employ any one of the standard elevating conveying means such as a belt, a belt provided with cleats, a bucket line, or a flight conveyer, but I prefer to use the latter and have illustrated the same in the embodiment of my invention herein shown. Referring to Figs. 2 and 5, it will be seen that the flight conveyer consists of a pair of chains 103 which are provided with the usual cross pieces 104 for carrying the material. These chains are mounted on and driven by sprockets 105 that are carried by shafts 106 journaled in bearings 107 secured to the frame members 14, 15. Suitable flooring 108 is provided within the path of the chains 103 so as to prevent the material from dropping away from the cross pieces 104. This flooring is fixed to and supported by cross bars 18, 19, 20, 21.

The flight conveyer chains 103 are driven through the shaft 106 which has one end projecting at the side of the machine and mounted in a bearing 109 carried on a bar 110 that is fast to the cross bars 16 and 18. A sprocket 111 is fixed on the said end of the

shaft 106 and connected by a chain 112 with another sprocket 113 that is on a short shaft 114 mounted in a bearing 115 fixed on a support 116 secured to the side of the framing. The other end of the shaft 114 has a bevel gear 117 that meshes with a similar gear 118 fixed on the adjacent shaft 74 from which power is derived for actuating the flight conveyer through the mechanism already described. 75

In order to lead the material from the digging elements 56, 59 up to the flight conveyer, I provide a feed board 119 (Figs. 2, 12 and 13) which is hinged on a pintle 120 that has its ends mounted in lugs 121 carried on the uprights 27, and is arranged to lead in a slanting direction upwardly from the bottoms of the digging arms to the flight conveyer. It will be observed that the angular or tilted mounting of the digging arms 85 causes the action of the digging elements to be such as to, of themselves, feed the material in an upward direction as it is passed on to the feed board 119, so that a continuous impulse is imparted to the material in 90 an upward direction which serves to facilitate its delivery to and full charging of the loading mechanism and particularly adapts the machine for the advantageous employment of means of the flight conveyer type. 95

Different adjustments of the digging arms will, owing to their angular arrangement, entail a different relationship with respect to the feed board 119 and the latter is, accordingly, made adjustable (Figs. 12 and 13) about the pivot 120 by providing it with arms 122 that are riveted to the sides of the feed board, as indicated at 123, and are curved upwardly with their free ends in engagement with bolts 124 that are fixed in 105 brackets 125 secured to the uprights 27. The bolts 124 are longitudinally adjustable by means of nuts 126 so as to swing the feed board 119 about its pintle or pivot 120 and thereby keep it in exactly proper relationship with respect to the digging arms so as to avoid the escape of material therebetween. 110

As an additional device for feeding the material onto the feed board 119, I provide, on each digging arm, a circular disc 127 (Figs. 7 and 10), which is, in each case, fixed to the shaft 49 so as to rotate therewith. The discs 127 are immediately below the cutting knives 59 and immediately above the feed board 119. It will be clear that 120 these discs serve to assist in forcing the material up onto the feed board and thence to the flight conveyer which forms part of the loading mechanism.

In the operation of the device, some of the 125 material may have a tendency to adhere directly to the plates 55° of the chain 55 and be carried along thereby instead of depositing on the feed board 119. In order to eliminate this, I provide a pair of scrapers (Figs. 126

2, 5 and 10), which consists of boards or plates 128 that are pivoted at 129 on the lower ends of the framing members 14, 15. These scrapers project so that their free ends 5 are adjacent the chains 55, in which position they are yieldingly held by coil springs 130. These scrapers are spaced a slight distance above the cutting knives 59 so that the latter may pass thereunder in their movement, this 10 being permissible owing to the fact that the said knives are so thin that this arrangement does not prevent the scrapers from removing the material from the entire width of the chain. In addition to the function just 15 described, the scrapers serve as side guides for the material which is being forced upwardly along the feed board 119 onto the flight conveyer.

In order to vary the angular adjustment 20 of the digging arms about the pivots 34, I provide reach rods 131 that are freely connected to the digging arms at 132, and have hooks on their rear ends adapted to enter any one of a series of eyes 133 that are 25 screwed in the frame members 12, 13. It will be plain that by hooking these rods 131 in different members of the sets of eyes 133, the degree of angularity of the digging arms with respect to each other will be varied so 30 that the width of their cut or path of operation will, correspondingly, be made wider or narrower. The machine also includes 35 mechanism for feeding the material from the top of the flight conveyer laterally so as to provide for dumping it into a vehicle. This means is shown in Figs. 1 to 4 inclusive and consists primarily of a conveyer belt 134. This belt is stretched about pulleys 135, 136 which are mounted in pairs of bearings 137 and 138. The bearings 137 are held 40 between arms 139 projecting from the outer ends of a pair of side beams 140 and the bearings 138 are mounted on arms 141 which project from the opposite ends of the said 45 beams 140. The pulley 136 is actuated by a sprocket 142 that is fixed to the end of its axle, which sprocket is connected by a chain 143 with another sprocket 144 that is mounted on a shaft 145 which is carried in 50 bearings secured to one of the framing uprights 24 and to additional uprights 146, 147 that are supported by the framing side members 12 and 22. The other end of the shaft 145 carries a sprocket 148 which is connected 55 by a chain 149 with a sprocket 150 on one of the shafts 74, from which latter power is derived for actuating the belt 134 as just described.

The side beams 140 are provided with a 60 pair of rollers 151 for supporting the upper portion of the belt and with a third roller 152 for supporting the lower portion thereof. Side boards 153 are carried by brackets 154 uprising from each side beam 140 in order 65 to retain the material on the belt 134.

The side beams 140 and connected parts are pivoted, as a whole, about an axle 155 that is carried by the uprights 146, 147, so that the free end of the belt may be brought to different heights for convenience in loading vehicles. This adjustment is effected by means 70 of cables 156 that pass through blocks 157 secured to the side beams 140 and the uprights 146 and 147. The free ends of the cables may be fastened to cleats 158 that are 75 on the said uprights 146 and 147.

I also provide means for adjusting the digging arms and connected mechanism, as a whole, about their mounting on the axle 9, which means consists of a cable 159 that 80 passes through block 160 secured to the frame member 2 and side framing member 12. The free end of this cable 159 is intended to be secured to a drum 161 that is fixed on the frame member 2 and may be operated 85 by a crank 162, the drum being provided with a pawl and ratchet, or similar mechanism (not shown). This adjustment not only enables the digging arms to be brought to the proper level for the intended operation, but enables the same to be lifted a considerable distance above the ground or street level when the machine is being dragged from one location to another.

It will be clear that the truck 93 not 95 only delivers power to the mechanism, as already described, but forces the machine forwardly into the material. I also provide that the truck may effectively steer the machine and to this end, connect the apex 100 of the supporting frame 23 by a swivel joint 163 to the tongue 92 carried on the truck, and see to it that this swivel joint 163 is substantially in alignment with the universal joint 89 in the power shaft. As 105 a result of this arrangement, the machine may be steered by turning the truck to the right or left which will swing the tail of the machine in the same direction and thus cause the machine to be guided in the opposite direction, as the case may be.

I believe that the operation of the machine will be sufficiently clear in the light of the foregoing description, but I may say that it is intended to be pushed forwardly 115 by the truck, with the digging arms set at the desired angle. As the machine is pushed forward, the material will be dug out and carried back onto the feed board, thence onto the flight conveyer and thence 120 onto the lateral feeding belt, from which it will be deposited into a vehicle for carting it away; or, this lateral feed of the belt may simply be for the purpose of depositing the material at one side. Thus, for instance, in attacking a heavy snow fall, the material may be dug out, carried upwardly and moved laterally so as to be deposited at the sides of the street, thereby rapidly and 125 thoroughly opening up a central path for 130

the use of vehicular traffic. The machine is peculiarly adapted for use in snow removal, since the knives 59 on the chain 55 serve to thoroughly cut under or break up any hard layer of snow or ice which may be closely adhering to the street surface, with a saw tooth action. These blades also serve to form, in conjunction with the digging blades 58 proper and plates 55^a, pockets for conveying the material rearwardly to the flight conveyer. In view of the fact that the digging arms are, as a whole elongated, I am enabled to obtain a jaw-like entrance into and operation upon the material with the digging blades clawing their way ahead into the material as they feed it back to the flight conveyer. This not only promotes the efficiency of the digging arms in actually removing the material, but, to a degree, assists in the forward movement of the machine as a whole. Furthermore, this shape and pivotal mounting of the digging arms gives rise to an unusual capacity for digging a path suitable to the conditions encountered and results which it is desired to obtain, even though the said path be relatively wide with respect to the machine; and also enables them to be swung together for convenient transporting and housing when out of operation. I, therefore, regard the elongated shape of these digging arms as a feature of material advantage.

It will be understood that various changes may be resorted to in the form, construction, means for propelling and actuating the machine, and arrangement of the several parts without departing from the spirit and scope of my invention, and hence, I do not intend to be limited to the details herein shown and described, except as they may be included in the claims.

What I claim is:

1. An apparatus of the character described comprising, a movable support, elongated digging arms carried thereby in V formation, digging and carrying elements mounted in the arms, and means for actuating the digging elements along the surface of the arms.

5. 2. An apparatus of the character described comprising, a movable support, elongated digging arms carried thereby, digging and carrying elements mounted in the arms, and means for actuating the digging elements along the surface of the arms, said digging arms being individually pivoted for horizontal adjustment.

6. 3. An apparatus of the character described comprising, a movable support, elongated digging arms carried thereby in V formation, digging and carrying elements mounted in the arms, and means for actuating the digging elements along the surface of the arms, said digging arms being individually pivoted for horizontal adjustment.

4. An apparatus of the character described comprising, a movable support, elongated digging arms carried thereby in V formation, digging and carrying elements mounted in the arms, and means for actuating the digging elements along the surface of the arms, said digging arms being tilted at an angle to the horizontal with their front edges downward. 70

5. An apparatus of the character described comprising, a movable support, elongated digging arms carried thereby, digging and carrying elements mounted in the arms, and means for actuating the digging elements along the surface of the arms, so said digging arms being individually pivoted for horizontal adjustment and being tilted at an angle to the horizontal with their front edges downward. 75

6. An apparatus of the character described comprising, a movable support, elongated digging arms carried thereby in V formation, digging and carrying elements mounted in the arms, and means for actuating the digging elements along the surface of the arms, said digging arms being individually pivoted for horizontal adjustment and being tilted at an angle to the horizontal with their front edges downward. 80

7. An apparatus of the character described comprising, a movable support, digging arms carried thereby, digging and carrying elements mounted in the arms, and means for conveying the material upwardly away from the digging and carrying elements, said digging and carrying elements being arranged to feed the material in an upward direction toward said conveying means. 10

8. An apparatus of the character described comprising, a movable support, digging arms carried thereby, digging and carrying elements mounted in the arms, means for conveying the material upwardly away from the digging and carrying elements, said digging and carrying elements being arranged to feed the material in an upward direction toward said conveying means, and a feed board intermediate the digging arms and the conveying means. 105

9. An apparatus of the character described comprising, a movable support, digging arms carried thereby, digging and carrying elements mounted in the arms, means for conveying the material upwardly away from the digging and carrying elements, said digging and carrying elements being arranged to feed the material in an upward direction toward said conveying means, and an adjustable feed board intermediate the digging arms and the conveying means. 110

10. An apparatus of the character described comprising, a movable support, elongated digging arms carried thereby, 120

- digging elements mounted in the arms, an endless carrier for actuating the digging elements along the surface of the arms in a substantially horizontal path, means for 5 conveying the material away from the digging arms, and means for removing any adhering material from the endless carrier.
11. An apparatus of the character described comprising, a digging arm, a flexible carrier mounted therein, and a series of digging elements supported by said carrier, each of said digging elements including a knife projecting and movable in an approximately horizontal plane.
15. 12. An apparatus of the character described comprising, a digging arm, a flexible carrier mounted therein, a series of digging elements supported by said carrier, each of said digging elements including a knife projecting and movable in an approximately horizontal plane, and a digging blade having its surface in a plane at an angle to the plane of the knife.
20. 13. An apparatus of the character described comprising, a digging arm, a flexible carrier mounted therein, a series of digging elements supported by said carrier, each of said digging elements including a knife projecting and movable in an approximately horizontal plane, a digging blade having its surface in a plane at an angle to the plane of the knife, and means for moving the series of blades inwardly and outwardly with respect to the surface of the carrier.
25. 14. An apparatus of the character described comprising, a digging arm, a flexible carrier mounted therein to travel in a path about a substantially vertical axis, digging elements on said carrier, and means connected to the upper part of the carrier for suspending it in its normal path of travel.
30. 15. An apparatus of the character described comprising, a digging arm, a flexible carrier mounted therein to travel in a path about a substantially vertical axis, digging elements on said carrier, and means connected to the upper part of the carrier for suspending it in its normal path of travel, said means including a track and a series of rollers, the one on the arm and the other on the carrier.
35. 16. An apparatus of the character described comprising, a digging arm, a flexible carrier mounted therein to travel in a path about a substantially vertical axis, digging elements on said carrier, and means connected to the upper part of the carrier for suspending it in its normal path of travel, said means including a track and a series of rollers, the one on the arm and the other on the carrier.
40. 17. An apparatus of the character described comprising, a digging arm, a flexible carrier mounted therein, digging elements on said carrier, means connected to the upper part of the carrier for suspending it in its normal path of travel, said means including a track and a series of rollers, the one on the arm and the other on the carrier, and means for keeping the said rollers in operative position with respect to the track.
45. 18. An apparatus of the character described comprising, a digging arm, a flexible carrier mounted therein, digging elements on said carrier, means connected to the upper part of the carrier for suspending it in its normal path of travel, said means including a track and a series of rollers, the one on the arm and the other on the carrier, and means for keeping the said rollers in operative position with respect to the track, said last named means including a second series of rollers adapted for engagement with a portion of the arm, one series of rollers being disposed to rotate in substantially vertical planes and the other series being disposed to rotate in substantially horizontal planes.
50. 19. An apparatus of the character described comprising, a digging arm, a flexible carrier mounted therein, digging elements on said carrier, means connected to the upper part of the carrier for suspending it in its normal path of travel, said means including a track and a series of rollers, the one on the arm and the other on the carrier, and means for keeping the said rollers in operative position with respect to the track, said last named means being disposed in a plane at an angle to the plane of rotation of the rollers.
55. 20. An apparatus of the character described comprising, a digging arm, a flexible carrier mounted therein, a series of digging elements supported by said carrier, and a rotatable disc independent of the digging elements mounted in said arm beneath said digging elements and adjacent the point where the digging elements are designed to deposit their load.
60. 21. An apparatus of the character described comprising, a movable support, a digging arm pivoted thereto, and digging elements mounted in the arm for movement in an endless path, the plane of movement of said elements being at an obtuse angle to the axis of the pivotal mounting of the arm.
65. 22. An apparatus of the character described comprising, a movable support, a digging arm pivoted thereto, digging elements mounted in the arm, mechanism in the arm for actuating the digging elements, drive mechanism on the movable support,

and a flexible connection between the drive mechanism and the actuating mechanism.

23. An apparatus of the character described comprising, a movable support, a digging arm pivoted thereto, digging elements mounted in the arm, mechanism in the arm for actuating the digging elements, drive mechanism on the movable support, and a flexible connection between the drive mechanism and the actuating mechanism, said flexible connection including a gear mounted in a floating bearing.

24. An apparatus of the character described comprising, a movable support, a digging arm carried thereby, digging elements mounted in the arm, a power shaft carried by the movable support, an independent unit for propelling the machine and providing power to said shaft, said independent unit being connected to the movable support and to said shaft by flexible connections arranged substantially in alignment with each other.

25. An apparatus of the character described comprising, a movable support, a digging arm carried thereby, digging elements mounted in the arm, an endless carrier for actuating the digging elements along the periphery of the arm, means for withdrawing the digging elements within the carrier with their operative faces in sliding contact with a portion of the carrier in order to remove the material from the elements, and means for removing any adhering material from the endless carrier.

26. An apparatus of the character described comprising, a movable support, a digging arm carried thereby, digging elements mounted in the arm, said digging elements including digging blades and cutting knives arranged to operate in planes at an

angle to each other, an endless carrier for actuating the digging elements along the periphery of the arm, means for withdrawing the digging blades within the carrier with their operative faces in sliding contact with a portion of the carrier in order to remove the material from the blades, and means for removing any adhering material from the endless carrier and knives.

27. An apparatus of the character described comprising, a movable support, an elongated digging arm carried thereby, digging elements mounted in the arm, an endless carrier for actuating the digging elements along the periphery of the arm, means for withdrawing the digging elements within the carrier with their operative faces in sliding contact with a portion of the carrier in order to remove the material from the elements, and means for removing any adhering material from the endless carrier.

28. An apparatus of the character described comprising, a movable support, an elongated digging arm carried thereby, digging elements mounted in the arm, said digging elements including digging blades and cutting knives arranged to operate in planes at an angle to each other, an endless carrier for actuating the digging elements along the periphery of the arm, means for withdrawing the digging blades within the carrier with their operative faces in sliding contact with a portion of the carrier in order to remove the material from the blades, and means for removing any adhering material from the endless carrier and knives.

In testimony, that I claim the foregoing as my invention, I have signed my name this 2nd day of October, 1922.

PIERPONT E. DUTCHER.
